US011933324B2

(12) **United States Patent**
Cooper

(10) **Patent No.:** **US 11,933,324 B2**
(45) **Date of Patent:** **Mar. 19, 2024**

(54) **MOLTEN METAL ROTOR WITH HARDEND BLADE TIPS**

(71) Applicant: **Molten Metal Equipment Innovations, LLC**, Middlefield, OH (US)

(72) Inventor: **Paul V. Cooper**, Chesterland, OH (US)

(73) Assignee: **Molten Metal Equipment Innovations, LLC**, Middlefield, OH (US)

(*) Notice: Subject to any disclaimer, the term of this patent is extended or adjusted under 35 U.S.C. 154(b) by 0 days.

(21) Appl. No.: **17/200,785**

(22) Filed: **Mar. 13, 2021**

(65) **Prior Publication Data**

US 2021/0199115 A1 Jul. 1, 2021

(57) **ABSTRACT**

Embodiments of the invention are directed to a rotor for use in molten metal and devices including the rotor. The rotor has a rotor body and blades, wherein each blade includes a tip that is at least twice as hard as the rotor body.

MOLTEN METAL ROTOR WITH HARDENED BLADE TIPS

CROSS REFERENCE TO RELATED APPLICATION

This application is a continuation of, and claims priority to U.S. patent application Ser. No. 15/013,879, filed on Feb. 2, 2016, by Paul V. Cooper which claims priority to U.S. Provisional Application Ser. No. 62/110,899 entitled "Molten Metal Rotor with Hardened Blade Tips," filed on Feb. 2, 2015. Each of the foregoing applications are incorporated herein in their entirety for all purposes.

FIELD OF THE INVENTION

The present invention relates to a rotor (also called an impeller) for pumping molten metal, the rotor having hardened blade tips. The purpose of the hardened blade tips is to decrease wear, and help prevent breakage, on portions of the rotor that are struck by dross or other hard objects found in molten metal.

BACKGROUND OF THE INVENTION

As used herein, the term "molten metal" means any metal or combination of metals in liquid form, such as aluminum, copper, iron, zinc and alloys thereof, in which devices according to the invention can function. The term "gas" means any gas or combination of gases, including argon, nitrogen, chlorine, fluorine, freon, and helium, that are released into molten metal.

Known molten-metal pumps include a pump base (also called a housing or casing), one or more inlets (an inlet being an opening in the housing to allow molten metal to enter a pump chamber), a pump chamber, which is an open area formed within the housing, and a discharge, which is a channel or conduit of any structure or type communicating with the pump chamber (in an axial pump the chamber and discharge may be the same structure or different areas of the same structure) leading from the pump chamber to an outlet, which is an opening formed in the exterior of the housing through which molten metal exits the casing. An impeller, also called a rotor, is mounted in the pump chamber and is connected to a drive system. The drive system is typically an impeller shaft connected to one end of a drive shaft, the other end of the drive shaft being connected to a motor. Often, the impeller shaft is comprised of graphite, the motor shaft is comprised of steel, and the two are connected by a coupling. As the motor turns the drive shaft, the drive shaft turns the impeller and the impeller pushes molten metal out of the pump chamber, through the discharge, out of the outlet and into the molten metal bath. Most molten metal pumps are gravity fed, wherein gravity forces molten metal through the inlet and into the pump chamber as the impeller pushes molten metal out of the pump chamber.

A number of submersible pumps used to pump molten metal (referred to herein as molten metal pumps) are known in the art. For example, U.S. Pat. No. 2,948,524 to Sweeney et al., U.S. Pat. No. 4,169,584 to Mangalick, U.S. Pat. No. 5,203,681 to Cooper, U.S. Pat. No. 6,093,000 to Cooper and U.S. Pat. No. 6,123,523 to Cooper, and U.S. Pat. No. 6,303,074 to Cooper, all disclose molten metal pumps. The disclosures of the patents to Cooper noted above are incorporated herein by reference, as are U.S. Pat. Nos. 7,402,276 and 7,507,367. The term submersible means that when the

pump is in use, its base and rotor are at least partially submerged in a bath of molten metal, and preferably fully submerged.

Three basic types of pumps for pumping molten metal, such as molten aluminum, are utilized: circulation pumps, transfer pumps and gas-release pumps. Circulation pumps are used to circulate the molten metal within a bath, thereby generally equalizing the temperature of the molten metal. Circulation pumps may be used in a reverberatory furnace 10 having an external well, or in any other suitable vessel that retains molten metal. The well is usually an extension of the charging well where scrap metal is charged (i.e., added).

Transfer pumps are generally used to transfer molten metal from the external well of a reverberatory furnace to a 15 different location such as a ladle or another furnace.

Gas-release pumps, such as gas-injection pumps, circulate molten metal while releasing a gas into the molten metal. In the purification of molten metals, particularly aluminum, it is frequently desired to remove dissolved gases such as 20 hydrogen, or dissolved metals, such as magnesium, from the molten metal. As is known by those skilled in the art, the removing of dissolved gas is known as "degassing" while the removal of magnesium is known as "demagging." Gas-release pumps may be used for either of these purposes or 25 for any other application for which it is desirable to introduce gas into molten metal. Gas-release pumps generally include a gas-transfer conduit having a first end that is connected to a gas source and a second submerged in the molten metal bath. Gas is introduced into the first end and 30 is released from the second end into the molten metal. The gas may be released downstream of the pump chamber into either the pump discharge or a metal-transfer conduit extending from the discharge, or into a stream of molten metal exiting either the discharge or the metal-transfer 35 conduit. Alternatively, gas may be released into the pump chamber or upstream of the pump chamber at a position where it enters the pump chamber. A system for releasing gas into a pump chamber is disclosed in U.S. Pat. No. 6,123,523 to Cooper. Furthermore, gas may be released into 40 a stream of molten metal passing through a discharge or metal-transfer conduit wherein the position of a gas-release opening in the metal-transfer conduit enables pressure from the molten metal stream to assist in drawing gas into the molten metal stream. Such a structure and method is disclosed in a copending application entitled "System for 45 Releasing Gas Into Molten Metal," invented by Paul V. Cooper, and filed on Feb. 4, 2004, the disclosure of which is incorporated herein by reference.

There are also pumping systems that include a rotor inside 50 of an essentially vertical conduit to drive molten metal upward into the conduit and out of an outlet in communication with the conduit. No pump base is used with such a system.

The materials forming the components that contact the 55 molten metal bath should remain relatively stable in the bath. Structural refractory materials, such as graphite or ceramics, that are resistant to disintegration by corrosive attack from the molten metal may be used. As used herein "ceramics" or "ceramic" refers to any oxidized metal (including silicon) or carbon-based material, excluding graphite, capable of being used in the environment of a molten metal bath. A ceramic is harder and more durable to impact with a hard substance than graphite. "Graphite" means any type of graphite, whether or not chemically treated. Graphite 60 is particularly suitable for being formed into pump components because it is (a) soft and relatively easy to machine, and (b) less expensive than ceramics.

When a molten metal pump, or pumping system, is operated, the rotor rotates, and the molten metal in which the rotor operates includes solid particles, such as dross and brick. As the rotor rotates the solid particles strike the moving rotor, potentially jamming or damaging the rotor and one or more of the other pump components, such as the rotor shaft.

Many attempts have been made to solve this problem, including the use of filters or disks to prevent solid particles from entering the inlet and the use of a non-volute pump chamber to increase the space between the inlet and rotor to allow solid pieces to pass into the pump chamber without jamming, where they can be pushed through the discharge by the action of the rotor.

SUMMARY OF THE INVENTION

The present invention relates to rotors used for pumping molten metal wherein the rotors have blades with hardened tips to alleviate damage to the rotor caused by dross or other hard particles striking the rotor as molten metal is pumped. The tips are at least twice as hard as the body portion of the rotor.

In one embodiment, the hardened tips are comprised of silicon carbide and the body portion is comprised of graphite. Aspects of the invention can be utilized on any molten metal rotor, whether used in a molten metal pump, a molten metal pumping system, a scrap melter, a degasser, or other device.

BRIEF DESCRIPTION OF THE DRAWINGS

FIG. 1 shows a front, perspective view of a rotor according to the invention.

FIG. 2 shows a top, perspective view of the rotor of FIG. 1.

FIG. 3 shows a side, perspective view of the rotor of FIG. 1.

FIG. 4 shows a side, perspective view of the rotor of FIG. 1 without the hardened tips.

FIG. 4A shows a rear view of a hardened tip used in the rotor of FIG. 1.

FIG. 4B shows a front view of a hardened tip used in the rotor of FIG. 1.

FIG. 5 shows a front perspective view of alternate version of a rotor in accordance with the invention.

FIG. 6 shows a top, perspective view of the rotor of FIG. 5 without the hardened tips.

FIG. 7 shows a rear, perspective view of a hardened tip used with the rotor of FIG. 5.

FIG. 8 shows a front, perspective view of a hardened tip used with the rotor of FIG. 5.

FIG. 9 shows a top view of a rotor according to aspects of the invention and having hardened tips of the structure shown in FIGS. 1-4B.

FIG. 9A shows a cross-sectional view of the rotor of FIG. 9.

FIG. 10 shows an alternate rotor according to aspects of the invention and having hardened tips of the structure shown in FIGS. 5-8.

FIG. 11 is a side view of the rotor of FIG. 9.

FIG. 12 is close-up, partial side view of the rotor of FIG. 10.

DETAILED DESCRIPTION OF PREFERRED EMBODIMENTS

As used herein the relative hardness of materials is determined by the MOHS hardness scale. On the MOHS

hardness scale, treated graphite (also referred to herein simply as graphite) is preferably used to form a rotor body according to the invention) generally has a hardness between 1.5 and 2.5 on the MOHS scale, whereas silicon carbide (preferably used to form a hardened tip according to the invention) generally has a hardness of 9-10 on the MOHS scale. By way of example, if a first material has a MOHS scale hardness of 1.0 and a second material has a MOHS scale hardness of 2.0, the second material is considered to be twice as hard as the first material for the purpose of this disclosure. Similarly, as an example, a third material with a MOHS scale hardness of 3.0 would be three times as hard as the first material and 50% harder than the second material for the purpose of this disclosure.

Turning now to the drawings, where the purpose is to describe preferred embodiments of the invention and not to limit same, systems and devices according to the invention will be described.

FIGS. 1-4B show one preferred rotor, and components thereof, according to aspects of the invention. Rotor 10 as shown preferably has a rotor body 100, three identical rotor blades (also called "vanes") 12, and hardened tips 200 on each blade. As used herein, a rotor blade (or "vane") is a structure separate from and spaced from other rotor blades, although a separate structure such as an outer ring may connect one or more blades. In rotor 10 each blade 12 as shown is curved inward on its leading surface 12A, meaning that it directs molten metal downward and outward (if the rotor is used on a top feed pump), or directs molten metal upward and outward if the rotor is used on a bottom feed pump, or in a system for pumping molten metal that directs the molten metal upward into a conduit. But, blades according to the invention may be of any suitable shape and size for the purpose for which they are used. A recess or trailing surface 12B as shown preferably extends from top surface 16 to bottom 14. The purpose of the angle or curve of trailing surface 12B is to reduce the area of top surface 16, thereby creating a larger opening for more molten metal to enter into the rotor 10 thus enabling rotor 10 to move more molten metal per rotor revolution and any suitable shape may be used for this purpose.

Rotor 10 may have a flow blocking and bearing plate 13. As shown, flow blocking and bearing plate 13 is cemented or otherwise attached to the bottom 14 of rotor 10. If rotor 10 is used on a bottom feed pump, the flow blocking and bearing plate 13 may be at the top of the rotor (in essence, the rotor would be turned upside down, with the blades 12 at the bottom, but the rotor shaft connective portion 18 would still be at the top of the rotor and formed through the flow blocking and bearing plate). The flow blocking and bearing plate 13 is preferably comprised of a hard, wear-resistant material, such as silicon carbide. Alternatively, a rotor according to the invention may not be attached to a flow blocking and bearing plate and any not have a bottom 14. For example, the rotor may be used in a system for moving molten metal upward into a conduit, or with scarp melter, or with a rotory degasser.

Rotor 10 further includes a connective portion 18, which is preferably a threaded bore, but can be any structure capable of drivingly engaging a rotor shaft (not shown) in order to rotate the rotor. It is most preferred that the outer surface of the end of a rotor shaft that is received in connective portion 18 has tapered threads and connective portion 18 be threaded to receive the tapered threads.

The preferred dimensions of rotor 10 will depend upon the size of the pump chamber or other structure in which the

rotor is received and/or used. If rotor **10** is positioned in a pump chamber, top surface **16** is preferably flush with the pump chamber inlet.

Hardened tips **200** are preferably at least: twice as hard as the body portion **100**, or 2-3 times harder than the body portion **100**, or 2-4 times harder than the body portion **100**, or 2-5 times harder than the body portion **100**, or 2-6 times harder, 2-7 times harder, 2-8 times harder, 2-9 times harder, 2-10 times harder than the body portion **100**. In one preferred embodiment, the body portion **100** is graphite and the tips **200** are silicon carbide.

Each hardened tip **200** preferably extends along at least part of top surface **16**, and as shown each hardened tip extends along part of the leading surface **12A** of each rotor blade **12**. Preferably, each hardened tip **200** forms at least: 15%, or at least 20%, or at least 25%, or at least 30%, or at least 35%, or at least 40%, or at least 50%, or at least 75%, or at least 90%, or 100%, or 30%-100%, of the leading edge **17** of rotor **10**.

The height of surface **12A** is measured from edge **17** to the upper surface of bottom **14**. Each hardened tip **200** also preferably extends downward along leading surface **12A** by at least: 10% of the height of surface **12A**, or at least 15% of the height of surface **12A**, or at least 20% of the height of surface **12A**, or at least 25% of the height of surface **12A**, or at least 30% of the height of surface **12A**, or at least 40% of the height of surface **12A**, or at least 50% of the height of surface **12A**, or at least 75% of the height of surface **12A**, or 30%-100% of the height of surface **12A**.

Each hardened tip **200** also preferably extends downward along the outermost edge of each vane **12** by at least: 15% of the height of surface **12A**, at least 20% of the height of surface **12A**, at least 25% of the height of surface **12A**, at least 30% of the height of surface **12A**. Each tip **200** also preferably extends along top surface **16** between leading edge **17** and trailing edge **19**, by at least: 10%, at least 20%, at least 30%, at least 40%, or at least 50%, or 30%-100% of the distance between leading edge **17** and trailing edge **19**.

FIGS. 4-4B shows body portion **100** and hardened tips **200** prior to being assembled. In order to secure the tips **200** to the body portion **100**, it is preferred that portions of the corners of each blade **12** on body **100** have cut-outs **70** to create channels **15**, and projections **210** on tips **200** are designed to snuggly fit into channels **15** when cemented in place. The mating of tips **200** to channels **15** helps secure tips **200** to body portion **100** and alleviate the possibility that they will come apart during use. Any suitable method, however, to connect tips **200** to body portion **100** may be used.

Additionally, as shown each cut-out **70** has a back channel **21** that mates with a corresponding extension section **221** on each tip **200** (which each has a top surface **220**) to help secure tips **200** to rotor body **100**. The tips **200** are preferably cemented in place in cut-outs **70**.

FIGS. 5-8 show an alternate preferred rotor according to aspects of the invention. Rotor **1000** as shown is in many respects the same as rotor **10** except for the shape of the rotor **1000** and the shape of the hardened tips **1200**. Rotor **1000** as shown preferably has a rotor body **1001**, three identical rotor blades (also called "vanes") **1012**, and hardened tips **1200** on each blade **1012**. In rotor **1000** each blade **1102** is dual flow, meaning that it has a first portion **1102A**, which as shown is entirely formed as part of tip **1200** although it need not be, that directs molten metal either downward or upward (downward if the rotor is used on a top-feed pump and upward if the rotor is used on a bottom-feed pump) towards a second

portion **1102B** that directs molten metal outward. However, blades according to the invention need not be dual flow.

Surface **1012A** is angled (as used herein the term angled refers to both a substantially planar surface, or a curved surface, or a multifaceted surface) such that, as rotor **1000** turns (as shown it turns in a clockwise direction) surface **1012A** directs molten metal towards second portion **1012B**. Any surface that functions to direct molten metal towards second portion **1012B** can be used, but it is preferred that surface **1012A** is substantially planar and formed at a 30°-60°, and most preferably, a 45° angle.

A recess or trailing surface **1012B** as shown preferably extends from top surface **1016** to bottom **1014**. Trailing surface **1012B** is flat and preferably dimensioned relative the size of rotor blade **1012** to help reduce the area of top surface **1016** on the blade, thereby creating a larger opening for more molten metal to enter into the rotor **1000** thus enabling rotor **1000** to move more molten metal per rotor revolution.

Rotor **1000** may have a flow blocking and bearing plate **1013**. As shown, flow blocking and bearing plate **1013** is cemented or otherwise attached to the bottom **1014** of rotor **1000**. If rotor **1000** is used on a bottom feed pump, the flow blocking and bearing plate **1013** may be at the top of the rotor (in essence, the rotor would be turned upside down, with the blades **1012** at the bottom, but the rotor shaft connective portion **1018** would still be at the top of the rotor and be formed through the flow blocking and bearing plate). The flow blocking and bearing plate **1013** is preferably comprised of a hard, wear-resistant material, such as silicon carbide. Alternatively, a rotor according to the invention may not be attached to a flow blocking and bearing plate and may not have a bottom **1014**. For example, the rotor may be used in a system for moving molten metal upward into a conduit, or with scarp melter, or with a rotory degasser.

Hardened tips **1200** are preferably at least: twice as hard as the body portion **1001**, or 2-3 times harder than the body portion **1001**, or 2-4 times harder than the body portion **1001**, or 2-5 times harder, or 2-6 times harder, or 2-7 times harder, or 2-8 times harder, or 2-9 times harder, or 2-10 times harder, than the body portion **1001**. In one preferred embodiment, the body portion **1001** is graphite and the tips **1200** are silicon carbide. As shown, each hardened tip **1200** extends along at least part of top surface **1016**, along part of the leading surface **1012A** of each rotor blade **1012**, and along part of the trailing surface **1012B** of each rotor blade **1012**.

Each hardened tip **1200** extends along at least part of top surface **1016**, and as shown each hardened tip extends along part of the leading surface **1012A** of each rotor blade **1012**. Preferably, each hardened tip **1200** forms at least: 15%, or at least 20%, or at least 25%, or at least 30%, or at least 35%, or at least 40%, or at least 50%, or at least 75%, or at least 90%, or 100%, or 30%-100%, of the leading edge **1017**. Each hardened tip **1200** also preferably extends downward along leading surface **1012A** by at least: 10% of the height of surface **1012A**, at least 15% of the height of surface **1012A**, at least 20% of the height of surface **1012A**, at least 25% of the height of surface **1012A**, at least 30%, or at least 40% of the height of surface **1012A**, or at least 50% of the height of surface **1012A**, or at least 75% of the height of surface **1012A**, or 30%-100% of the height of surface **1012A**, or at least the entire height of surface **1012A**. The height of surface **1012A** is measured from surface **1016** on edge **1017** to the upper surface of bottom **1014**.

Each hardened tip **1200** also extends downward along the outermost edge of each vane **1012** by at least: 15% of the height of surface **1012A**, at least 20% of the height of surface **1012A**, at least 25% of the height of surface **1012A**,

at least 30% of the height of surface **1012A**, at least 40% of the height of surface **1012A**, at least 50% of the height of surface, at least 75% of the height of surface **1012A**, or 30%-100% of the height of surface **1012A**. Each tip **1200** also preferably extends along top surface **1016** between leading edge **1017** and trailing edge **1019**, by at least 10%, at least 20%, at least 30%, at least 40%, at least 50%, at least 75%, or 30%-100%, of the distance between leading edge **1017** and trailing edge **19**.

Each hardened tip also preferably forms part of and extends along at least 10% of the height of back surface **1012B** (as measured from top surface **1016** to the top of bottom **1014**), at least 20% of the height of back surface **1012B**, at least 30% of the height of back surface **1012B**, at least 40% of the height of back surface **1012B**, or at least 50% of the height of back surface **1012B**, at least 75% of the height of surface **1012B**, or 30%-100% of the height of back surface **1012B**.

Rotor **1000** further includes a connective portion **1018**, which is preferably a threaded bore, but can be any structure capable of drivingly engaging a rotor shaft (not shown). It is most preferred that the outer surface of the end of a rotor shaft that is received in connective portion **1018** has tapered threads and connective portion **1018** be threaded to receive the tapered threads.

The preferred dimensions of rotor **1000** will depend upon the size of the pump chamber or other structure in which it is received and/or used. If rotor **1000** is positioned in a pump chamber, top surface **1016** is preferably flush with the pump chamber inlet.

FIGS. 6-8 show body portion **1001** and hardened tips **1200**, each of which as an extension **1210**, prior to being assembled. In order to secure the tips **1200** to the body portion **1001**, it is preferred that portions of the corners of each blade **1012** on body portion **1001** be cut out to create recesses or gaps **1015** and tips **1200** are designed to snuggly fill gaps **1015** when cemented in place. The mating of tips **1200** to gaps **1015** helps secure tips **1200** to body portion **1001** and alleviate the possibility that they will come apart during use. Any suitable method, however, for attaching hardened tips **1200** to rotor body portion **1001** may be used.

Additionally, as shown each gap **1070** has a channel **1015** and a back channel **1021** that mate with corresponding sections on each tip **1200** to help secure tips **1200** to rotor body **1001**. The tips are preferably cemented in place.

FIGS. 9 and 11 show a rotor **1100** that has the same hardened tip design as rotor **10**. Rotor **1100** has blades **1102**. Each blade **1102** has a leading surface **1104**, a hardened tip **1105**, and a trailing surface **1108**. Rotor **1100** also has a flow blocking plate **1110**, a connective portion **1112**, and a rotor body portion **1101**, which as used throughout this specification for each embodiment is the body of the rotor that does not include the flow blocking plate, or bearing(s), and that is softer than the hardened tip(s).

FIG. 9A is a cross-sectional, side view of the rotor of FIG. 9.

FIGS. 10 and 12 show a rotor **1200** that has the same hardened tip design as rotor **1000**. Rotor **1200** has blades **1202**. Each blade **1202** has a leading surface **1204**, a hardened tip **1206**, and a trailing surface **1208**. Rotor **1200** also has a connective portion **1212**, and a rotor body portion **1201**.

Hardened tips may be utilized in any suitable rotor, such as the rotors described in U.S. Pat. Nos. 7,402,276, 8,178,037, 8,110,141, 8,409,495, and 8,075,837.

Having thus described some embodiments of the invention, other variations and embodiments that do not depart

from the spirit of the invention will become apparent to those skilled in the art. The scope of the present invention is thus not limited to any particular embodiment, but is instead set forth in the appended claims and the legal equivalents thereof. Unless expressly stated in the written description or claims, the steps of any method recited in the claims may be performed in any order capable of yielding the desired result.

10 What is claimed is:

1. A rotor for use in molten metal, the rotor comprising (a) a body portion, and (b) a plurality of rotor blades, wherein each rotor blade comprises (i) a leading edge on a leading surface, wherein the leading surface has a height, (ii) a trailing edge, (iii) a top surface between the leading edge and the trailing edge, and (iv) a separate hardened tip different from and not connected to a hardened tip on any of the other plurality of rotor blades and comprising material at least twice as hard as the body portion, wherein the hardened tip extends along the top surface 30%-50% of a distance between the leading edge and the trailing edge and 30%-50% of the leading edge.

2. The rotor of claim 1, wherein each separate hardened tip is comprised of material between 2-3 times, 2-4 times, or 2-5 times as hard as the body portion.

3. The rotor of claim 1, wherein each separate hardened tip is cemented to the body portion.

4. The rotor of claim 1, wherein each separate hardened tip is comprised of silicon carbide and the body portion is comprised of graphite.

5. The rotor of claim 1, wherein each rotor blade has a first portion and a second portion, and the first portion pushes the molten metal towards the second portion, and the second portion pushes the molten metal outward.

6. The rotor of claim 5, wherein each separate hardened tip forms at least part of the first portion.

7. The rotor of claim 6, wherein each separate hardened tip forms part of the second portion.

8. The rotor of claim 5, wherein each rotor blade includes a recess on the side opposite the first portion, each recess for enlarging an opening between each rotor blade to allow more molten metal to pass through the opening.

9. The rotor of claim 1, wherein the body portion has grooves formed in each rotor blade, wherein the grooves are configured to receive a corresponding extension of each hardened tip.

10. The rotor of claim 1, wherein the plurality of blades comprises three blades.

11. The rotor of claim 1 that further includes a connective portion configured to connect to a rotor shaft.

12. The rotor of claim 1 that further includes a flow-blocking plate at a bottom of the rotor.

13. The rotor of claim 1 that further includes a bearing surface comprised of ceramic.

14. The rotor of claim 5, wherein the first portion of each rotor blade has a horizontally-extending projection with a top and with a bottom.

15. The rotor of claim 5, wherein the second portion of each rotor blade is vertical.

16. The rotor of claim 14, wherein the bottom surface of each horizontally-extending projection is formed at a 10°-60° downward angle relative a horizontal axis.

17. The rotor of claim 14, wherein the horizontally-extending projection has the leading edge and the leading edge is at least $\frac{1}{8}$ " thick.

18. The rotor of claim 1, wherein each separate hardened tip extends along part of each leading surface.

19. The rotor of claim 1, wherein each rotor blade has an outermost edge and the separate hardened tip of each rotor blade extends along part of the outermost edge.

20. A molten metal pump including the rotor of claim 1.
